VOLTAGE REGULATOR TUBE

John Milton Pomfrett, Emporium, Pa., assignor to
 Hygrade Sylvania Corporation, Salem, Mass.,
 a corporation of Massachusetts

Application January 25, 1939, Serial No. 252,739

1 Claim. (Cl. 250—27.5)

This invention relates to voltage regulator tubes and more especially to tubes of the type employing a gaseous discharge for voltage regulation.

A principal object is to provide a voltage regulator tube of the cathode glow type which possesses high operating stability even at relatively low current drains in the system to which it is connected.

Another object is to provide gaseous voltage regulator tubes of the cathodic glow type with a construction such that the electrical characteristics of large batches of tubes are uniform, thus enabling the tubes to be manufactured in large quantities with uniformity of results when the tubes are used in circuits whose voltage is to be controlled.

Another object is to provide an improved gaseous voltage regulator tube wherein the electrodes are so constructed and arranged as to insure a definite "breakdown" voltage.

A feature relates to a voltage regulator tube of the gaseous discharge type wherein the electrodes are constructed and arranged so that the "breakdown" voltage is always in excess of the "operating" voltage.

A further feature relates to the novel organization, arrangement and relative location of parts which constitute a more efficient and stable voltage regulator tube of the cathodic glow discharge type.

Other features and advantages not specifically enumerated will be apparent after a consideration of the following detailed descriptions and the appended claim.

Referring to the drawing, there is illustrated one preferred embodiment wherein Fig. 1 is an elevational view, partly sectional, of a tube according to the invention.

Fig. 2 shows a series of curves explanatory of the operation of the tube of Fig. 1.

While electric gaseous tubes of the cathodic glow discharge type have been proposed heretofore as voltage regulators in many kinds of electrical circuits, considerable difficulty has arisen because the "breakdown" or striking potential has been very close to the operating or "keep alive" potential. This is especially true where the tube has an "operating" potential which is in excess

of 100 volts. In this latter case where the "breakdown" potential is equal to or less than the "operating" potential, considerable instability occurs when the device is used with circuits of low current drain. For example, where the tube is used to regulate the anode or grid

potential of an audio amplifier tube, such as is used for example in radio receivers and the like, this instability is the cause of much noise in the output of the amplifier. I have found that this disadvantage, amongst others, can be overcome by proper design and location of the starting electrode with respect to the cathode and anode of the regulator tube, and as a result of which the "breakdown" potential is always in excess of the operating potential.

Referring to Fig. 1, there is shown a typical embodiment wherein the tube, which may be of any configuration, comprises an enclosing envelope 1 of glass or metal. In the case of the glass envelope, it is provided with the conventional reentrant stem 2 terminating in a press 3, wherein are sealed the various lead-in wires 4, 5 and 6. The wire 5 is connected to a metal rod which, at its lower end, is sealed into the press 3. Rod 8 constitutes the anode of the tube and may be of nickel, or other suitable metal. Likewise, a pair of lateral metal support rods 9 and 10 are sealed into the press, rod 9 being connected to lead-in wire 4. Welded or otherwise fastened to the side rods, 9, 10, is a tubular or cylindrical metal electrode 11 which functions as the cathode. Electrode 11 may be of any suitable metal such for example as nickel, and may have its inner surface activated or unactivated. For example, the cathode surface 30 may be activated by coating it with electron-emissive material wellknown in the radio tube art. Preferably, the anode 8 is circular in cross-section and is mounted so as to be concentric with cathode 11.

Attached to the inner face of cathode 11 adjacent the upper end, is a starting electrode 12 which may be of nickel, or other suitable metal, which is preferably bent to L-shape with the horizontal part of the L extending radially inward toward the anode 8 so that the said horizontal part is in line or approximately so with the upper end of the cathode. The vertical part of electrode 12 may be welded to cathode 11. In accordance with the invention, the horizontal arm of electrode 12 extends inwardly so as to be closely adjacent to, but slightly spaced from, anode 8, for example this spacing may be about 1 mm.

In order to preserve the concentric relation and spacing of the electrodes, a pair of insulator discs 13, 14, may be assembled over the rods 9, 10 and anode 8. These discs may be of mica and fastened in place in any manner wellknown in the radio tube art, for example by being pro-

vided with metal eyelets which are welded to the rods 9 and 10. The discs 13 and 14 closely fit against the upper and lower ends of the cathode so as to confine the discharge to the inner surface of the cathode. Preferably, the portion of anode 8 which extends beneath mica disc 13 is provided with an insulator protective sheath in the form of a glass or ceramic tube 15, thus confining the discharge to the space enclosed by the cathode 11 and discs 13, 14. A getter support 16 carrying a suitable "getting" material may be connected to wire 17 which is sealed into the press and connected to lead-in wire 6. If desired, the disc 14 may contact resiliently with the dome of bulb 1 in any manner wellknown in the radio tube art to steady the electrode assembly against shock or vibration. The envelope 1 is filled with a suitable gaseous atmosphere such as a mixture of one or more of the rare gases, and pressure and nature of this gas mixture and the nature of the cathode surface determining the voltage regulation characteristics as is wellknown in the art of gaseous discharge tubes.

In manufacturing the tube, the glass envelope 1 is carefully exhausted while being heated at a temperature of approximately 450° C. for approximately 15 minutes. The envelope is allowed to cool, after which the cathode is heated to redness by any well-known means, for example by high frequency induction, until all occluded gases are removed therefrom. The getter material on support 16 is then flashed to perfect the vacuum, and the device may then be filled with the proper gas or gas mixture at a predetermined pressure after which the envelope is sealed off in the well-known manner. The bulb may be provided with any well-known form of shell base 18 carrying the contact prongs 19 to which the various lead-in wires are connected. While Fig. 1 shows a base of the "Octal" type, it will be understood that this is merely illustrative.

Fig. 2 illustrates the voltage "E" against current "I" characteristics of the two types of voltage regulator devices the curve designated A represents the voltage current characteristics of a tube such as shown in Fig. 1 wherein the start-

ing electrode is located near one end of the cathode 8, while the remaining curves B1, B2 and B3 show the characteristics for tubes where the starting electrode is located near the center of the cathode structure. It will be observed that with a tube such as shown in Fig. 1 and illustrated by curve A, the "breakdown" voltage is in excess of the "operating" voltage, whereas in the curves B1, B2 and B3 the "breakdown" voltage is less than the "operating" voltage. The tubes with the characteristic B therefore, show unstable operation and noisy performance whereas the tube of Fig. 1 exhibits stability of operation and freedom from noise. It has been found that with the construction of Fig. 1, the discharge is always initiated between the starting electrode and the anode, this "breakdown" voltage being slightly higher than the rated operating voltage. After the discharge is initiated, the cathodic glow travels along the surface of the cathode, the amount of the discharge depending upon the current being drawn. Probably one explanation for this is that placing the starting electrode as shown in Fig. 1, it is located at a point where the field strength between the anode and cathode is relatively weaker than exists between the anode and the central portion of the cathode.

While one specific embodiment of the invention has been disclosed, it will be understood that this is done merely for explanatory purposes, and that various changes may be made in the disclosed embodiment without departing from the spirit and scope of the invention.

What I claim is:

An electric regulator tube of the gaseous discharge type comprising a sealed envelope containing a gaseous filling, an anode and a cathode of materially different surface areas with the one of larger area being the cathode and surrounding the anode, a starting electrode attached to the inner surface of the cathode adjacent one end thereof and having a portion extending into close proximity to the corresponding end of the anode for maintaining the "breakdown" potential higher than the operating potential.

JOHN MILTON POMFRETT.
